UNITED STATES PATENT OFFICE

168,364

TIRE

James Walter Martin, Wichita, Kans.

Application February 16, 1951, Serial No. 14,244

Term of patent 14 years

(Cl. D90—20)

To all whom it may concern:

Be it known that I, James W. Martin, a citizen of the United States of America, residing in the city of Wichita, county of Sedgwick, State of Kansas, have invented a new, original, and ornamental Design for Tires, of which the following is a specification, reference being had to the accompanying drawing, forming a part thereof, and in which

Fig. 1 is a perspective view of a tire, showing my new design;

Fig. 2 is a fragmentary top plan view thereof; and

Fig. 3 is a fragmentary side elevational view of the same.

I claim:

The ornamental design for a tire, as shown.

JAMES WALTER MARTIN.
